(57) **CLAIM**

The ornamental design for a camera handle for a surgical light head, as shown and described.

DESCRIPTION

FIG. 1 is a top perspective view of a first embodiment of a camera handle for a surgical light head showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a top perspective view of a second embodiment of a camera handle for a surgical light head showing our new design;

FIG. 10 is a bottom perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and

FIG. 16 is a bottom plan view thereof.

FIG. 17 is a top perspective view of a third embodiment of a camera handle for a surgical light head showing our new design;

FIG. 18 is a bottom perspective view thereof;

FIG. 19 is a front elevational view thereof;

FIG. 20 is a rear elevational view thereof;

FIG. 21 is a left side elevational view thereof;

(Continued)

FIG. 22 is a right side elevational view thereof;
 FIG. 23 is a top plan view thereof; and
 FIG. 24 is a bottom plan view thereof.
 FIG. 25 is a top perspective view of a fourth embodiment of a camera handle for a surgical light head showing our new design;
 FIG. 26 is a bottom perspective view thereof;
 FIG. 27 is a front elevational view thereof;
 FIG. 28 is a rear elevational view thereof;
 FIG. 29 is a left side elevational view thereof;
 FIG. 30 is a right side elevational view thereof;
 FIG. 31 is a top plan view thereof; and
 FIG. 32 is a bottom plan view thereof.
 FIG. 33 is a top perspective view of a fifth embodiment of a camera handle for a surgical light head showing our new design;
 FIG. 34 is a bottom perspective view thereof;
 FIG. 35 is a front elevational view thereof;
 FIG. 36 is a rear elevational view thereof;
 FIG. 37 is a left side elevational view thereof;
 FIG. 38 is a right side elevational view thereof;
 FIG. 39 is a top plan view thereof; and,
 FIG. 40 is a bottom plan view thereof.

In all embodiments, the broken line showing is for the purpose of illustrating unclaimed portions of the article and forms no part of the claimed design.
